ABSTRACT OF THE DISCLOSURE

A heat pipe is provided with means in the evaporator section for reducing the effective capillary pore diameter of that portion of the wick. The effective size of the pores in the evaporator wick are varied in response to an external signal and the pressure differential which drives the circulating fluid is thereby controlled.

BACKGROUND OF THE INVENTION

Field of the invention

The present invention relates generally to the field of heat transfer systems and in particular to controlled thermal conductance pipes.

DESCRIPTION OF THE PRIOR ART

Prior to the present invention if it were desirable to vary the heat flux at a given temperature or the temperature at a given heat flux in a heat pipe it was necessary to introduce a volume of a non-condensable gas into the heat pipe tube to reduce the condenser area. This gas operated to control the temperature of the vapors in the heat pipe but was not effective to control the terminal temperature nor is this approach amenable to proportional and independent control in response to an external applied signal. Further disadvantages of this means of heat flux control revolve about the complexity of the plumbing apparatus required, the expense involved in its use, the size of the gas reservoir, and the insufficient accuracy with which the control could be effected.

OBJECTS AND SUMMARY OF THE INVENTION

It is thus a primary object of the present invention to provide a new and novel controllable heat pipe.

It is another object of the present invention to provide apparatus of the above-described character having a proportionally controlled evaporation rate and/or terminal temperatures.

It is an additional object of the present invention to provide apparatus of the above-described character wherein the effective pore size of the evaporator wick is varied in response to an externally applied signal.

These and other objectives of the present invention are achieved by providing a heat pipe having a generally cylindrical evaporator section with a wick disposed about its inside surface. A cylindrical spiral spring is disposed inside the wick such that in its uncompressed state the spring has an outside diameter less than the inside diameter of the evaporator wick. A spring compression means is provided which may operate in response to an external control signal to force the spring radially against the wick surface thereby reducing the effective capillary diameter. An increase in the vapor velocity in the evaporator and an increase in the evaporation rate is thus provided.

The foregoing as well as other objects, features and advantages of the present invention will become more apparent from the detailed description taken in conjunction with the appended drawings.

BRIEF DESCRIPTION OF THE DRAWINGS

FIG. 1 is a schematic cross sectional view of a con-

2

trollable heat pipe evaporator in accordance with the principles of the present invention.

FIG. 2 schematically illustrates an alternative embodiment of the present invention.

DESCRIPTION OF PREFERRED EMBODIMENT

Turning now to FIG. 1 there is illustrated in schematic longitudinal cross section a heat pipe evaporator section constructed in accordance with the principles of the present invention. The remainder of the heat pipe is not shown in the interests of clarity. A generally cylindrical heat pipe tube 10 has a conventional fixed wire mesh type wick 12 disposed around its inner surface. Also conventional in form is a source of heat flux 14 disposed in a heat transfer relationship to the tube 10. Heat from the source 14 operates to evaporate a liquid phase working fluid from the wick 12 and the vapors move under a slight pressure differential toward the condenser end (not shown) of the heat pipe. One of the significant factors influencing the performance of a heat pipe is the rate at which evaporation of liquid from the wick 12 occurs and a means for externally controlling this factor permits control of the heat flux and/or temperature at any point in the heat transfer system. To this end the present invention includes a cylindrical spiral spring 16 having a spacing between the adjacent turns in the uncompressed state which is equal to or greater than the wire mesh 12 size. When the spring 16 is compressed, it reduces the effective capillary pore diameter of the wick 12, thus decreasing the radius of curvature of the liquid meniscus. The pressure differential across the meniscus is thereby increased resulting in an increase in vapor velocity and evaporation rate. The spring 16 is compressed in response to an externally applied control signal. In the embodiment shown in FIG. 1 the compression of spring 16 is effected by a magnetic slug 18 disposed within the heat pipe tube 10 and which moves axially along the tube under a magnetic field set up by an external solenoid coil 20 driven by an evaporator control means 22. The force exerted on the slug 18 and thus the amount of compression of the spring 16 is approximately proportional to the square of the electric current from the control means 22 passing through the coil 20. In this manner the effective size of the pores in the evaporator wick 12 surface is varied by an independently acting means, thus controlling the pressure differential which drives the circulating fluid. It will be apparent that the evaporator control means 22 may be coupled to and controlled by the output of a temperature sensor 24 affixed to the heat flux source 14 thereby providing a simple, independent, proportional control of heat flux and/or temperature. Further the evaporator control means 22 may be made responsive to other signals derived from any other variable in the heat transfer system and may be coupled through an appropriate servo-mechanism to provide a closed control loop.

FIG. 2 schematically illustrates an alternative embodiment of the present invention wherein elements common to those shown in FIG. 1 are identified with like reference numerals. In this embodiment of the invention the heat pipe tube 10, evaporator wick 12, heat flux source 14, and cylindrical spiral spring 16 are identical in structure and function to the like elements described hereinabove with reference to FIG. 1. In this case, however, spring 16 compression is achieved by a piston 26 coupled by an actuating rod 28 to a hydraulic, pneumatic or thermal expansion actuator 30. The axial distance through which the actuator 30 drives the piston 26 is determined by the electrical output signal from an evaporator control means 22. As discussed hereinabove the evaporator control means 22 may be coupled to a temperature sensor

(not shown) to thereby provide closed loop proportional control of the heat pipe evaporator.

It will be apparent that the applicant has provided a new and novel heat pipe having means for the proportional control of the evaporation rate, the heat flux, or any other measurable variable in the heat transfer system, in response to an externally applied signal. The objectives set forth above are thereby efficiently met and, since certain changes may be made in the above-described construction without departing from the scope of the invention, it is intended that all matter contained in the foregoing description or shown in the appended drawings shall be interpreted as illustrated and not in a limiting sense.

Having described what is new and novel and desired to secure by Letters Patent, what is claimed is:

1. An improved heat transfer apparatus of the type characterized as including a closed container having an evaporator section coupled to a heat source, a condenser section coupled to a heat sink, and a capillary structure saturated with a volatile fluid and disposed on the interior surfaces of said container and wherein said improvement comprises

a spiral spring disposed within and coaxially aligned with said capillary structure,

means for providing axial compression of said spring to thereby radially compress said capillary structure, and

means adjacent said spring for restricting axial movement thereof and against which said spring may be compressed.

2. Apparatus as recited in claim 1 wherein said capillary structure is a mesh wick.

3. Apparatus as recited in claim 2 wherein the spacing between turns of said spring in its uncom- pressed state is no greater than the size of said mesh.

4. Apparatus as recited in claim 2 wherein

said spring compressing means comprises a magnetic slug disposed within said evaporator section of said container in axial alignment with said spring,

a solenoid coil disposed externally about a portion of 40 said evaporator section of said container, and

a variable source of electric current coupled to said coil whereby spring compression proportional to the square of said electric current is provided.

5. Apparatus as recited in claim 4 further including a thermal sensor coupled to said heat transfer apparatus and having the output thereof coupled to and operative to control the output of said current source whereby automatic proportional control of the thermal conductance of said heat transfer apparatus is provided.

6. Apparatus as recited in claim 2 wherein said spring compressing means comprises a piston disposed within said evaporator section of said container in axial alignment with said spring piston actuating means disposed external to said container and coupled through said container to said piston, and means for controlling the output pressure of said actuating means.

7. Apparatus as recited in claim 6 further including a sensor coupled to said heat transfer apparatus and having the output thereof coupled to and operative to control the output of said pressure controlling means whereby automatic proportional control of the thermal conductance of said heat transfer apparatus is provided.

8. Apparatus as recited in claim 6 wherein said actuating means is a hydraulic actuator.

9. Apparatus as recited in claim 6 wherein said actuating means is a pneumatic actuator.

10. Apparatus as recited in claim 6 wherein said actuating means is a thermal expansion actuator.
